HEAT EXCHANGER SECTION

James Whiteley, Detroit, Mich.

Application April 25, 1934, Serial No. 722,402

1 Claim. (Cl. 257—230)

This invention relates to heater sections for fuel economizers or other structures wherein the heat is transferred to another medium as for instance water in the production of steam, and the object 5 of the invention is to provide a structure through which the fluid to be heated is introduced in a cold state and from which it passes in a heated state, which structure is of a simple and inexpensive form and in which greater areas than heretofore usual are subjected to the influence of heat, and further a feature and object of the invention is to provide a simplified construction thereby decreasing the manufacturing cost thereof and at the same time exposing maximum surfaces of the 10 fluid container to heat.

It is also an object of the invention to provide a new and improved heater section to be used in a series within a shell through which heated gases flow in which sections the fluid to be heated 15 is passed and each of which sections involve a pair of headers and a series of flat tubular elements extending between the headers and welded thereto, the tube walls being externally supported against individual deformation or relative displacement through influence of pressure or heat.

It is further an object of the invention to provide a section of the general character above stated in which the interiors of the tubular elements are open to inspection and free throughout 20 their lengths for introduction of a cleaning implement from the exterior of the section.

It is also an object of the invention to provide 25 a heater section having externally supported tube walls and headers of a construction to permit ready removal of the tubes therefrom.

These and other objects and the several novel 30 features of the invention are hereinafter more fully described and claimed, and the preferred form of construction of a heater section for use in conjunction with economizers or other purpose is shown in preferred form in the accompanying drawings in which—

Fig. 1 is a vertical section of a fuel economizer 35 showing in elevation my improved sections arranged in series.

Fig. 2 is an enlarged view in similar section.

Fig. 3 is a sectional view taken longitudinally 40 of the section on line 3—3 of Fig. 2.

Fig. 4 is a sectional view showing the sealing 45 plug for the cleanout opening provided in the section.

Fig. 5 is an alternative form of construction 50 showing a means of supporting the tube walls

and yet permitting a comparatively ready disassembly thereof from the tubes.

Fig. 6 is a section taken on line 6—6 of Fig. 5.

In Fig. 1 I have shown generally a fuel economizer as one of the purposes of use of my improved heater section construction in which the sections are arranged in series in superposed relation, the lower section 1 of which is open to a supply line 2 and the successive sections are connected together by U pipe bends 3, 4 etc. 5. The arrangement of the bends is such that the inlet to a section is at one end and the outlet 10 thereof is on the opposite end and connected to the adjacent end of the next section of the series, that is, the bend 3 connects the end of the lower section 1 of the series shown in Fig. 1 with the adjacent end of the next section 5 of the series and the bend 4 connects the opposite end of the section 5 with the adjacent end of the section 6 15 etc., throughout the series and, depending upon the purpose for which the section is used, a considerable number of sections may be associated in the relation stated.

It is to be noted that, in the arrangement of 20 the sections 1, 5, 6 etc., the sections are in staggered relation for a purpose hereinafter stated. In the particular use in an economizer the sections are arranged in groups between which is provided a soot blower 7, 8 and 9 respectively 25 which forms no part of this present invention. More properly speaking, the invention resides in the section rather than in the arrangement of the sections for any particular purpose as it will be obvious that the section of the construction and form shown provides a large area in surface 30 contact with heated gases and has a number of uses other than as a fuel economizer.

The structural features of my improved heater 35 section are shown more clearly in Figs. 2 and 3 in which it will be observed that each section comprises a rectangular shaped header 9 and a similar header 10 between which extends a series of parallel tubes 11, 11 shown in dotted lines in Fig. 2 and in elevation in Fig. 3. From Fig. 2 it will be observed that these tubes are flat-walled tubes. 40 By using this form of tube a greater number of tubes may be positioned in a section of a certain length of header than is possible if the tubes were round for instance and further that a greater surface of tubes is scoured by the heated gases flowing 45 between the tubes, there being less of the tube at the upper side shielded from the gases by the construction shown than is the case with the round tube.

The sections are made up of two headers which 50

are originally of channel form having an upper and lower horizontal wall and the outer or end wall 12. The dotted lines 13 in Fig. 2 define the interior end portions of the top and bottom walls. 5 The flattened tubes of the desired length are secured at their opposite ends to the tube plates 14 and 15, which plates are shown in Fig. 3 as forming the inner walls of the headers 9 and 10. These plates have apertures fitting the tube, the form 10 in cross section of which is shown in dotted lines in Fig. 2. On the tubes are also provided a series of plates 16, 16 each having apertures through which every tube of the section extends and in which the tubes practically fit. These plates 16 15 are placed in comparatively closely spaced relation on the tubes and extend parallel with the headers and after these plates are in place, the tube plates 14 and 15 are welded to the tube ends and the plates 14 and 15 then welded in the headers. 20

The plates 16 have a double function. With a flat tube, pressure within the tube tends to deform the walls and the plates thus serve to prevent such deformation by internal pressure. Further, the tubes being subjected to heat and being of comparatively thin metal, the tube itself tends to warp or become displaced relative to the other tubes intermediate the ends. Each of these plates 16, which are shown in dotted lines in Fig. 2, 25 enclose the entire group of tubes in a section and serve to prevent or limit any material relative displacement of the tubes through heat so at all times the tubes are maintained throughout their lengths in spaced relation and provide free passageways for gas therebetween. 30

It will be noted particularly from Fig. 2 that the sections are offset so that a tube of a lower section is directly beneath a space between the pair of tubes of the next section thereabove. Thus 40 gases that pass between a pair of tubes in a lower section are directed against the tube of the next above section. By this arrangement the hot gases are continuously deflected as they pass upward through the various sections and the maximum 45 heat is absorbed from the gases in flowing over the sections. In this respect it will be readily noted that the hot gas stream passing between two tubes of a lower section has the sides of the gas stream in contact with said tubes and the central portion 50 of the gas stream being out of direct contact with the first two tubes has lost less of its heat than the portions in contact with the tubes and this more highly heated central portion of the 55 heated gases is directed against the lower side of an upper tube and caused to take a path upwardly around its side walls and thus continuously the hottest portion of the gases are deflected to contact with the wall of the tubes carrying the fluid to be heated.

In the construction of a fuel economizer such as is herein suggested, the sections may be supported by angle irons 17, 17 on opposite side walls and a deflector or baffle 18 is provided at one end of one section and at the opposite end of the next section throughout the series which arrangement insures the positioning of the sections in the staggered or offset relation above described. The baffle 65 prevents passage of any material portion of the gases around the sections.

It will be noted that the tubes are free from 70 internal obstruction and open to the headers and, as shown in Fig. 2, there is a plug 19 provided in the outer wall 12 of each header for sealing the aperture which is of a diameter, in 75 the construction shown, sufficiently large to pro-

vide access to three tubes through which a cleaning implement may be passed from the exterior of the headers. In Fig. 1 is shown a series of plugs 19 (the blank holes simply diagrammatically representing the plugs) and an opening of approximately the same diameter is provided for the connection of the conduits 2, 3, 4 etc. Such conduit as is illustrated at 3 in Fig. 2 being on the end of the section opposite the end provided with the plugs shown on the left side 10 of the said figure. On the right side is shown the ends of the conduits connecting the sections shown in Fig. 2 with the section below the lower section and the section above the upper sections. The preferable form of plug for use in 15 the headers is shown in Fig. 4. It consists of a tapered member 20 having a threaded stem 21. A packing ring 22 is provided in the aperture and a plate 23 provides a cover for the aperture through which the stem extends and which cover may be integral with the nut if so desired. By turning the nut the tapered plug is drawn down against the packing ring and seals the opening. Also, the taper of this plug is such 20 that internal pressure within the header tends to seat the plug. Other forms of plug may be used, however, without departing from the spirit of this invention.

The fuel economizer shown simply consists of a shell 25 having an opening 26 at the bottom 30 through which heated gases may pass as for instance from a boiler, and a hood 27 is provided at the top for an exhaust stack but this general character of construction is simply diagrammatic. The upper section of the series also 35 has a relief valve 28 provided thereon and is connected to a pipe line 29 which may lead to the boiler or other apparatus to which the heated fluid is to be discharged. A blow-off valve 30 40 may be provided.

In the construction as hereinbefore described and with the plates 16 mounted on the tubes 11 in which they are practically a press-fit, it is difficult to withdraw a tube from the headers and while there are many constructions in which such an arrangement is desirable and practical there are a number of installations where it is desirable that the tubes be readily removable. For this purpose I have shown in Figs. 5 and 6 45 a means for supporting the walls of the tube from deformation by internal pressure that is capable of being disassembled from the tubes. The header is shown in Fig. 5 at 12^a and the tubes are shown at 11^a in section. Above and below the tubes are the bars 30 and 31 which support the plates 32, as shown in Fig. 6, that extend from one bar to the other in contact with the side walls of the tube. The plates or bars 32 have the U ends 32^a to loosely receive the 50 bars 30 at one end and 31 at the opposite end 55 as shown in Fig. 6.

The bars 30 and 31 are threaded at the ends and the ends extend through apertures in an end plate or bar 33. Nuts 34 on the ends of 60 these bars 30 and 31 are utilized to tighten up the entire structure holding the tubes in pressure contact with the alternate plates or bars 32 whereby they are supported from deformation 65 by internal pressure. These bars 30 and 31 are spaced apart similarly to the plates 16 of Fig. 3 and thus there are a series of plates or bar like members 32 at short distances apart longitudinally of each tube 11^a and the same purpose is 70 achieved by this latter construction as is at 75

tained by the construction described relative to the structure shown in Fig. 3.

It will be seen from the foregoing description that the invention resides in the construction 5 of the heater section and that the various objects of the invention are obtained by the construction described, namely, a comparatively simple and inexpensive heater section which is highly efficient in use due to the form of the 10 tubes and the manner in which the tubes are supported against distortion or displacement through pressure or heat; that the sections are readily cleaned and that, by arranging the sections in staggered relation, a highly efficient 15 heating system for fluid is obtained and also that the metal plates on the tubes materially assist in transferring heat to the fluid in the tubes.

Having thus briefly described my invention, its utility and mode of operation, what I claim and desire to secure by Letters Patent of the United States is—

A heater section for use in boilers, fuel economizers and the like comprising a pair of headers, a series of tubes opening at opposite ends to the respective headers, a series of plates separating the tubes and lying in contact with the side walls thereof and in spaced relation longitudinally of the tubes between the headers, and means for applying pressure to the series of plates and interposed tubes whereby the plates through contact with the side walls of the tube under pressure prevent deformation of the tubes 15 through internal pressure. 5

JAMES WHITELEY.
